UNITED STATES PATENT OFFICE.

JAMES H. JONES, OF CLEVELAND, OHIO.

WASHING MACHINE.

Application filed April 2, 1924, Serial No. 703,708. Renewed December 1, 1928.

The objects of the invention are to provide a simple, efficient and practical method of construction for the cylinder of a washing machine in which a metal construction is 5 preferably employed. This cylinder is enclosed in an outer casing and its cover is preferably composed of woven wire material in order to permit the cleansing solvent to obtain freer access to the fabrics enclosed therein, and to enable it to act more 10 effectually upon the same.

The invention comprises, the fabric washing cylinder and trunnion bearing extremities or heads therefor, and means for securing the edges of the cylinder wall to the circumferential edges of said heads without the use of rivets in the construction, since rivets often become loose and the fabrics may catch upon them and become torn and 20 ruined thereby.

To overcome this difficulty the cylinder is composed of a perforated wall and disc shaped heads, the circumferential edges of which are grooved to provide seats or interlocking means for the edges of the cylinder wall, and a frame is provided by connecting the trunnion discs together by means of 25 longitudinal spaced bars, which not only serve as connecting or binding means for the discs, but are provided with retaining means for the perforated material of which the cylinder wall is composed, and also serve 30 as a bracing and strengthening means for the cylinder and serve as raising and distributing means for the fabrics enclosed in the cylinder. Also disc shaped partitions 35 separate the cylinder into compartments and are secured to the covering material.

The retaining means for the perforated material of the wall may comprise longitudinal grooves in the longitudinal outer edges of said bars and circumferential grooves in the edges of the said trunnion discs, and partitions, which are formed to receive molten metal in which the edges of the perforated material or attaching devices are locked, thus providing a solid integrally constructed device with no loose or projecting parts that can tear the cloths. 45

The outer edges of the perforated cover material are turned inwardly and are embedded in the molten metal in the circumferential edges of the trunnion discs, and are rigidly secured in this manner. 50

The body of the perforated cover material is secured to the longitudinal ribs by turn-

ing down its edges and embedding them in molten metal poured into the grooves therein.

Also sliding doors are provided for door 60 openings which are formed between the partitions and are so constructed that they will have no projecting parts upon which the fabrics may catch, and no openings in which the fabrics may catch or through 65 which they may work out of the cylinder, will occur at their edges.

This feature is essential, particularly in the use of large machines where the weight of the fabrics in falling impart a con- 70 siderable amount of pressure thereto.

Also a locking device for the doors is provided which is designed not only to lock the doors securely when the machine is in operation but is also constructed and ar- 75 ranged to lock the cylinder to the outer casing of the machine when the doors are open, and thus to prevent movement of the cylinder in the outer casing.

This feature is of great importance since 80 with its use it will be impossible for any one to start the machine, when the door is open.

In operation, when the door lock is withdrawn it will automatically engage in a re- 85 cess in the outer wall of the machine and the door cannot be opened until the bolt is so engaged.

The invention further includes the combination and arrangement of parts and construction of details hereinafter described 90 and illustrated in the accompanying drawings and specifically pointed out in the claims.

In the accompanying drawings Fig. 1 is 95 a perspective of the washing machine. Fig. 2 is a circumferential section showing the door in its frame. Fig. 3 is a plan thereof and Fig. 4 a transverse section thereof. Fig. 5 is a transverse section of the entire 100 cylinder on a reduced scale. Fig. 6 is a longitudinal section of one end thereof. Fig. 7 is a transverse section enlarged, of one of the reinforcing ribs showing the means for locking the perforated material thereto. Fig. 8 is a similar section of the rim bordering the door opening. Fig. 9 is a plan 105 of a portion thereof. Fig. 10 is a longitudinal section of one end of the cylinder and one door.

In these views A, is the stationary en- 110 closure or casing in which the cylinder B,

is rotatably mounted. The complete cylinder comprises a frame composed of the trunnion discs D, D, mounted on trunnions D', D', and spaced longitudinal bars H, H, 5 provided with spaced perforations H', H', rigidly connecting the said discs, and spaced partitions I, I, connecting the bars at intervals, thus separating the interior of the cylinder into compartments. This frame is 10 preferably covered by means of sheets of perforated material E, openings being left at J, J, for the movements of the doors as shown in Figs. 1, 2, 3, and 5.

All the ribs are longitudinally grooved 15 at K, K, and the circumferential edges of the partitions are also grooved at L, L, and the edges of the trunnion discs are grooved at M.

To rigidly attach the circumferential 20 edges of the perforated material to the trunnion discs, they are turned inwardly and inserted in the grooves M and sealed therein by molten metal poured therein at M'. To rigidly lock the material upon the 25 longitudinal ribs, these ribs are similarly grooved at K, K, and the edges of the material are turned downward therein and retained in place by means of molten metal P, poured therein.

If desired, further security may be provided by means of T-shaped bars Q, Q, embedded in the molten metal and turned over 30 edges R, of the grooves as shown in Figs. 7 and 8. In Fig. 8 a longitudinal rib that is 35 marginal to the front edge of one of the door openings is shown. This rib is provided with an integral flange T⁶, into which the edges of the door T, may enter.

Preferably the edge of the flange is 40 grooved at T⁴ to engage the edge of the door T, to prevent the contents of the cylinder from coming out of the opening. Also the circumferential edges of the partitions are grooved at L, L, and the perforated material passing thereover is locked 45 thereto by means of molten metal at X, X, (Fig. 6) in the grooves. Locking means such as staples Y, Y, which are engaged in the perforated material and have their extremities immersed in the molten metal may 50 be employed.

For further locking action the outer edges Z, Z, of the walls of these grooves may be turned inwardly thus preventing the escape 55 of the metal, and loose action of the material.

The perforated material may be made in sections extending from one longitudinal rib to another and having its ends secured in 60 the manner described in the longitudinal grooves, as shown in Figs. 7 and 8.

The doors are slidingly movable in the door openings and their rear edges when the doors T, T, are closed, are interlocked as 65 shown in Figs. 2 and 3 with the turned over

edges T', T', of the flange T², T², upon the edge of the adjacent covering material.

This construction prevents the contents of the cylinder from coming out. See Fig. 3.

The front edge of the door is formed at 70 T³, to form a bar which enters a groove or socket T⁴ in the edge of the flange T⁵ upon the adjacent rib.

The flange T⁵ is provided with a guide T⁶ in which a bolt T⁷ slides.

The bolt when the door is opened enters a recess T⁸, in the inner face of the outer casing A, and prevents the cylinder from revolving until the door is securely closed at 80 which time the bolt is drawn from the outer casing and the lug T⁹ thereon engages the plate T¹⁰ in the door and prevents the door from opening. In this manner the bolt has the dual purpose of locking the door and also alternately therewith locking the cylinder from moving so that the cylinder cannot move or the machine start until the bolt has been withdrawn from the casing and the door closed.

In Fig. 10 the doors T are shown to be 90 provided with inwardly turned circumferential edges, forming grooves therein and complementary engaging grooved edges T¹¹, T¹¹, are attached, preferably by welding, to the edges of the grooves in the trunnion disc, 95 and partitions. These grooved edges form guides upon which the doors slide.

Having described the invention, what I claim as new and desire to secure by Letters Patent is:

1. In a washing machine a cylinder frame composed of discs mounted on trunnions and longitudinal reinforcing bars connecting said discs, and intermediate transverse partitions connecting said bars, the circumferential edges of said discs and partitions and the outer edges of said bars being grooved, a cylindrical perforated wall for said cylinder, said wall being composed of longitudinal sections, and the edges of said sections being inserted in the grooves in adjacent parts of said bars and discs and metallic means for integrally connecting said edges with said adjacent metal parts.

2. In a washing machine a cylinder frame composed of disc shaped heads provided with trunnions, longitudinal reinforcing bars connecting the same, and transverse partitions intermediate of said heads, the edges of said discs, bars and partitions being externally grooved, a cylindrical wall for said frame formed of longitudinal portions each composed of wire netting the edges of said wall portions being inserted in said grooves in said discs and bars, and fastening means for the portions of said wall that pass over the outer edges of said partitions, said fastening means being attached to said wall and entering said grooves in said partition, and a sealing positioned in all said grooves 130

for integrally securing said wall edges and fastening means in place.

3. In a washing machine a cylinder frame composed of disc shaped heads provided with trunnions, reinforcing bars connecting said heads and intermediate transverse partitions connecting said bars, the circumferential edges of said discs, and partitions and the longitudinal edges of said bars being grooved a cylindrical wall for said cylinder, said wall being composed of longitudinal portions, and formed of perforated material, the edges of said wall portions being inserted in said grooves in said discs and bars, and fastening means for those portions of said wall that pass over said partitions, said fastening means being attached to said wall and entering said grooves in said partitions and a molten metal seal in all said grooves for integrally securing said wall edges and fastening means in place and means for retaining said molten metal in said grooves.
4. In a washing machine a cylinder frame composed of disc shaped heads provided with trunnions, reinforcing bars connecting said heads and intermediate transverse partitions connecting said bars, the circumferential edges of said discs, and partitions and the longitudinal edges of said bars being

grooved a cylindrical wall for said cylinder, 30 said wall being composed of longitudinal portions, and formed of perforated material, the edges of said wall portions being inserted in said grooves in said discs and bars, and fastening means for those portions 35 of said wall that pass over said partitions, said fastening means being attached to said wall and entering said grooves in said partitions and a molten metal seal in all said grooves for integrally securing said wall 40 edges and fastening means in place, and means for retaining said molten metal in said grooves, and means for retaining said molten metal in place.

5. In a washing machine a frame composed of trunnion bearing discs, longitudinal bars and transverse partitions and perforated wall sections, each disc being provided with an attachable marginal channel member and each partition being circumferentially grooved, and said bars being longitudinally channelled, to provide receptacles for molten metal in which the edges of said wall sections are immersed.

In testimony whereof, I hereunto set my hand this 8th day of March, 1924.

JAMES H. JONES.
